United States Patent

Des. 238,685

Patented Feb. 3, 1976

238,685

FLIGHT DATA COMPUTER

Charles S. Walters, 61st Ave., Plantation, Fla. 33317

Filed May 28, 1974, Ser. No. 473,403

Term of patent 14 years

Int. Cl. D14—02; D18—01

U.S. Cl. D26—5 C

FIG. 4

FIG. 3

FIG. 2

FIG. 1 is a front perspective view of a flight data computer, showing my new design;

FIG. 2 is a front elevational view thereof;

FIG. 3 is a right side elevational view thereof, the left side being substantially a mirror image thereof;

FIG. 4 is a top plan view thereof.

I claim:

The ornamental design for a flight data computer, as shown and described.
